UNITED STATES PATENT OFFICE

90,643

DESIGN FOR A RADIATOR CAP

John Lee Baldwin, Babylon, N. Y.

Application February 8, 1933. Serial No. 47,150

Term of patent 3½ years

To all whom it may concern:

Be it known that I, JOHN LEE BALDWIN, a citizen of the United States, residing at Babylon, in the county of Suffolk and State of New York, have invented a new, original, and ornamental Design for Radiator Caps, of which the following is a specification, reference being had to the accompanying drawing, forming part thereof.

The figure is a perspective view of a radiator cap, showing my new design.

I claim:

The ornamental design for a radiator cap, as shown.

JOHN LEE BALDWIN.
